CLAIM

The ornamental design for a golf bag as shown and described.

DESCRIPTION

FIG. 1 is a first side perspective view of a golf bag; FIG. 2 is a second side perspective view of the golf bag of FIG. 1;

FIG. 3 is a second side view of the golf bag of FIG. 1;

FIG. 4 is a first side view of the golf bag of FIG. 1;

FIG. 5 is a front view of the golf bag of FIG. 1;

FIG. 6 is a rear view of the golf bag of FIG. 1;

FIG. 7 is a top view of the golf bag of FIG. 1; and,

FIG. 8 is a bottom view of the golf bag of FIG. 1.

The broken lines of the drawing show portions of the golf bag that form no part of the claimed design.

1 Claim, 7 Drawing Sheets
